CAN OPENER

Oscar H. Hanby, Grandview, Wash.

Application September 15, 1949, Serial No. 115,850.

6 Claims. (Cl. 30—4)

1

This invention relates to can openers and in particular to those of the type adapted to be driven by an electric motor or other source of power.

An object of the invention is to provide an improved can opener that is of comparatively simple construction and yet highly efficient and safe and reliable in operation.

Another object is to provide a can opener that is entirely automatic in operation and need never be touched by human hands either to start or stop the same.

Another object is to provide a can opener of the motor driven type in which the cutting cycle is initiated by pressure from the can and in which only one hand is required for use, that being the hand in which the can is held while the machine is opening it thus leaving the other hand of the housewife free to hold a saucepan or other culinary vessel ready for transferring the contents of the can.

The foregoing and other objects and advantages inherent in the invention will become more apparent from the following detailed description of a preferred constructional embodiment and the accompanying drawings in which:

Fig. 1 is a view in side elevation.

Fig. 2 is a front elevation.

Fig. 3 is a transverse section taken on line 3—3 of Fig. 2.

Fig. 4 is a transverse section taken on line 4—4 of Fig. 2.

Figs. 5 and 6 are sectional views similar to Fig. 3 illustrating the positions of the components during different phases of the operating cycle; and Fig. 7 is a schematic wiring diagram of the driving motor and its two control switches.

Referring now to the drawings; the can opener includes a support plate 10 having a transverse bracket 11 attached thereto for fastening the same in an upright position on the wall of the kitchen or other room where it is desired to locate the device. The electric driving motor 12 is secured to plate 10, and the motor shaft 13 which is arranged horizontally is provided with a small pinion gear 14 that meshes with a larger diameter reduction gear 15 that is keyed or otherwise secured upon the end of another horizontally arranged shaft 16. The latter is journaled in a yoke 17 secured to plate 10, and is provided with a worm gear 18 between the yoke arms 17a that meshes with a worm wheel 19 secured upon the upper end of a generally vertically disposed drive shaft 20. The latter is journaled at its upper end in a yoke 21 that is carried by the shaft 16. The lower end of drive

2

shaft 20 is journaled in a bracket 22 secured to plate 10, and this bracket has an intermediate offset portion 22a that permit it to yield slightly in a horizontal direction to accommodate cans having different bead thickness.

Secured to the lower end of the drive shaft 20 is a knurled feed roller 23 adapted to engage the inner side of the bead 24a at the top of the can 24, and also a cam 25.

10 The lower end of plate 10 projects horizontally at 10a and pivotally connected at 26 to the latter is a carriage 27 on which is mounted a guide roller 28 and a cutter element which is preferably also formed as a roller 29 with a peripheral knife edge portion 29a.

15 When carriage 27 occupies the position shown in Fig. 3 and to which it is always returned upon completion of a cutting cycle, there is sufficient clearance between the feed roller 23 and the cutter and guide rollers 28, 29 to insert the top bead of the can to be opened. When the motor 12 is started, cam 25 rotates into engagement with a lug 30 on the carriage, and as the cam continues to rotate bearing against this lug, carriage 27 is displaced horizontally about its pivot axis 26 in the direction of the feed roller 23 to the position shown in Fig. 5 causing the top bead 24a of the can to be gripped firmly between the rotating feed roller 23 and guide roller 28, and the knife edged periphery 29a of cutter 29 punctures the side wall of can 24 just below bead 24a.

20 Displacement of the carriage in the direction of the feed roller 23 and its return to the starting position is limited by stop pins 31, 32, fixed to the horizontal offset 10a of the support plate. Due to the pressure of the knurled feed roller on the can bead, the can body will then begin to rotate causing the cutter 29 to make a continuous peripheral cut through the can body along a line just below the bead 24a.

25 As previously explained, control of the mechanism is automatic and the motor is started whenever a can is presented for cutting. To bring this about, it will be observed that an arcuate guide plate 33 depends from the horizontal offset 10a. This plate guides the can into cutting position, and also serves as a broad bearing surface for the can side wall to maintain the can in correct vertical alignment with respect to the rollers while being cut. A switch unit 34 is

30 mounted upon the support 10 at the general level of the guide plate 33 and the switch contacts are actuated by a push rod 35 that projects through an opening 33a in plate 33. As is clear from the drawing, one end of rod 35 extends beyond the inner face 33b of plate 33 and is adapted to be

pushed in by the side wall of can 24 to a position substantially flush with the inner face 33b. The other end of rod 35 is adapted to bear against the contact operating member of the switch. Switch 34 is of the well known "push button" type, i. e. the switch contacts are self releasing and are closed only when pressure is applied against the switch button by rod 35 as the latter is shifted to the left from the position shown in Fig. 1. When the rod pressure is removed, the switch contacts reopen automatically.

Rod 35 is loaded by spring 36 to the right, i. e. in the direction away from switch 34 and hence the contacts of the switch will be closed only during such time as rod 35 is pressed to the left by the can wall. As will be seen from the schematic circuit diagram in Fig. 7, a circuit between the motor 12 and its source of power is completed via the switch contacts 34b and conventional appliance plug connector 37 assuming the latter to be plugged into a convenient outlet whenever the switch contacts are closed thus setting the drive shaft 20 into rotation.

Provision is also made for returning the carriage 27 to its starting position and stopping the motor after the top of the can has been completely severed and the can removed. To this end, it will be seen that the carriage is provided with a trip lever 38 pivotally mounted at 38c intermediate its ends, and the position of the lever is determined by the position of rod 35 through an operating link 39, one end of link 39 being connected to rod 35 and the other end connected to end 38a of lever 38. The linkage arrangement is such that the other end 38b of the trip lever is moved out of the path of the cam 25 as shown in Fig. 5 whenever rod 35 is shifted to the left from the position shown in Fig. 1, i. e. during the period in which a can is being opened, and into the cam path as shown in Fig. 6 whenever rod 35 occupies its other position.

For stopping the motor 12 upon completion of a cutting cycle, a second switch 40 is utilized. This switch which operates on the same principle as switch 34 is mounted upon the support plate 10a in such position that the switch lever 40a is pressed inwardly by an adjustable screw type abutment 41 on carriage 27 to close the switch contacts 40b as the carriage 27 is moved by cam 25 from the position in Fig. 3 to that of Fig. 5. As seen in Fig. 7, the contacts 40b of switch 40 are connected in parallel with switch contacts 34b to keep the motor energized after pressure is released from rod 35 and contacts 34b open as shown in Fig. 6.

As explained above, so long as rod 35 is pressed inwardly by the can i. e. during the time that the can wall is being cut, the end 38b of trip lever 38 is held out of the path of the cam 25 and consequently the latter rotates free of the trip lever for as many revolutions of the feed roller 23 as are required to rotate the can through one revolution. After the can has been cut completely around its periphery, the housewife who in the meantime should preferably support the can bottom loosely in hand while it is slowly revolving is now free to remove the opened can from the machine. This of course releases the pressure upon rod 35 causing switch contacts 34b to open and the end 38b of the trip lever to move into the path of rotation of cam 25 as viewed in Fig. 6. Motor 12, however, continues to run due to the holding circuit established through now closed switch contacts 40b. When cam 25 engages the trip lever end 38b, the force exerted thereon by the cam is transmitted through the pivot 38c to

the body of carriage 27, causing the latter to return to its starting position as shown in Fig. 3. The severed can top is thereby released from the feed and guide rollers 23, 28 and the contacts 40b of switch 40 are opened as pressure upon switch lever 40a by abutment 41 is released thus disconnecting motor 12 from the power source. This action completes the operating cycle and the can opener is ready for a repeat operation.

A cover member 42 is preferably provided to enclose motor and gear mechanism thus exposing only the rollers, cutter and guide plate to view, and may be secured in place on wall bracket 11 by means of screws 43 at each side thereof.

In conclusion it will be evident that the machine is entirely automatic and need never be touched by hand either to start or stop the same. Also only one hand, namely the one in which the can is held is required for operation of the machine, leaving the other hand free which is often of utmost convenience to the housewife. Moreover, while the construction illustrated in the drawings illustrates a practical embodiment, it does not by any means exhaust all design possibilities. Hence I wish it to be expressly understood that various structural changes may be made therein without departing from the spirit and scope of the inventive principles involved as expressed by the appended claims.

I claim:

1. In a motor driven can opener, the combination comprising a fixed support, a drive shaft rotatably mounted on said support and coupled to said motor, for rotation in one direction only, a cam and feed roller carried by and rotatable with said shaft, a carriage pivotally mounted upon said support, said carriage including thereon a cutter member, a guide cooperative with said feed roller and a lug engaged by said cam upon initial rotation thereof for effecting a turning movement of said carriage about its pivot mounting in the direction of said feed roller to thereby cause the can bead to be gripped between said guide and feed roller and the can side wall to be punctured by said cutter member, and a trip member mounted upon said carriage and cooperative with said cam for returning said carriage to its initial position, said trip member being retained in a non-operative position by the can body while the latter is being cut but movable into the path of said cam upon removal of the opened can to thereby effect the said carriage return by continued rotation of said cam in the same direction of rotation.

2. In a can opener, the combination comprising a fixed support, a drive shaft rotatably mounted on said support, a cam and feed roller carried by and rotatable with said shaft in a given direction, a carriage mounted upon said support for movement relative thereto, said carriage including thereon a cutter member, a guide cooperative with said feed roller and a lug engaged by said cam upon initial rotation thereof for moving said carriage in the direction of said feed roller to thereby cause the can bead to be gripped between said guide and feed roller and the can side wall to be punctured by said cutter member, and a tripping device effective upon completion of the cutting operation for returning said carriage to its initial position, said tripping device being engageable with and actuatable by said cam upon continued rotation of the latter in said given direction.

3. In a can opener, the combination comprising a fixed support, a drive shaft rotatably mounted

on said support, a cam and feed roller carried by and rotatable with said shaft, a carriage mounted upon said support for movement relative thereto, said carriage including thereon a cutter member, a guide cooperative with said feed roller and a lug engaged by said cam upon initial rotation thereof for moving said carriage in the direction of said feed roller to thereby cause the can bead to be gripped between said guide and feed rollers and the can side wall to be punctured by said cutter member, and a carriage trip member mounted upon said carriage and cooperative with said cam, said trip member being retained in a non-operative position by the can body while the latter is being cut but movable into the path of said cam upon removal of the opened can for effecting a return of said carriage to its initial position upon continued rotation of said cam in the same direction.

4. In a motor driven can opener, the combination comprising a drive shaft coupled to said motor, a cam and feed roller carried by said shaft, a carriage supporting thereon a cutter member, a guide cooperative with said feed roller and a lug engaged by said cam upon initial rotation thereof for moving said carriage in the direction of said feed roller to thereby cause the can bead to be gripped between said guide and feed roller and the can side wall to be punctured by said cutter member, means adapted to be actuated by the can body when brought into position for engagement by said rollers for starting said motor, and means effective upon subsequent removal of the opened can from the cutting position to return said carriage to its initial position and stop said motor.

5. In a motor driven can opener, the combination comprising a support, a drive shaft on said support, a motor on said support, means coupling the motor shaft to said drive shaft, a feed roller and cam carried by said drive shaft, a carriage mounted on said support for displacement relative to said drive shaft, said carriage having thereon a cutter member, a guide cooperative with said feed roller and a lug engaged by said cam upon initial rotation thereof for displacing said carriage in the direction of said drive shaft to thereby cause the can bead to be gripped between said guide and feed roller and the can side wall to be punctured by said cutter member, a normally open switch for connecting said motor to a source of power and which is adapted to be closed only upon application of pressure to a

switch actuating member from the can when brought into position for engagement by said rollers, a trip member on said carriage controlled by said switch actuating member and movable into the path of said cam upon removal of the opened can to thereby return said carriage to its initial position, and a second switch connected in parallel with the other said switch and which is controlled by said carriage, said second switch being closed when said carriage moves to its displaced position and opened when returned to its initial position.

15 6. In a motor driven can opener, the combination comprising a support, an upright drive shaft on said support, a motor on said support, means coupling the motor shaft to said drive shaft, a feed roller and cam carried by said drive shaft, a carriage pivotally mounted on said support for horizontal displacement relative to said drive shaft, said carriage having thereon a cutter member, a guide cooperative with said feed roller and a lug engaged by said cam upon initial rotation thereof for displacing said carriage in the direction of said drive shaft to thereby cause the top bead of the can to be gripped between said guide and feed roller and the can side wall to be punctured by said cutter member, a normally open switch for connecting said motor to a source of power and which is adapted to be closed only upon application of pressure to a switch actuating member from the can when brought into position for engagement by said rollers, a trip member on said carriage controlled by said switch actuating member and movable into the path of said cam upon removal of the opened can to thereby return said carriage to its initial position, and a second switch connected in parallel with the other said switch and which is controlled by said carriage, said second switch being closed when said carriage moves to its displaced position and opened when returned to its initial position.
